UNITED STATES PATENT OFFICE.

JOHN F. AMES, OF PORTLAND, OREGON.

FONT OF TYPE.

SPECIFICATION forming part of Letters Patent No. 715,936, dated December 16, 1902.

Application filed February 6, 1901. Serial No. 46,189. (No specimens.)

To all whom it may concern:

Be it known that I, JOHN F. AMES, a citizen of the United States, residing at Portland, county of Multnomah, State of Oregon, have 5 invented an Improvement in Fonts of Type; and I hereby declare the following to be a full and clear description of the same.

My invention relates to the manufacture of fonts of type such as are employed for printing upon the material of wooden boxes, &c.; and it consists of the improved font of type which I will hereinafter describe and claim.

In the accompanying drawing, forming part of this specification, the figure illustrates 15 a group of type constructed according to my invention.

In using type for imprinting words and characters upon surfaces under heavy pressure it is necessary to use a very hard metal 20 in order to prevent the printing-faces of the type or characters from being crushed and broken by a pressure upon the hard surface and when such type are locked in the form and in position to print upon the surface 25 they will spring or bulge out by reason of the great pressure which is brought upon them as the material passes beneath the printing-cylinder.

My invention is designed to use this class 30 of hard-metal type and to provide a means for interlocking them in the form, so that they will be prevented from bulging or being otherwise displaced.

As shown in the drawing, A represents type 35 made of brass or equivalent hard metal, having a character on one end and having substantially the entire surface of two opposite sides grooved at 2 in parallel transverse lines, which extend from edge to edge of the body.

40 The arrangement of the grooves is such that the depressions of one type will interlock with

the elevations of an adjacent type throughout the height of the bodies of the type, which interlocking will maintain the impression-surfaces at all times in proper relation with 45 each other to insure a clean and perfect print.

In addition to the foregoing each of the type has a channel 3 formed in one edge parallel with the character-bearing face and at 50 right angles to the corrugations. This groove is useful in locking the type in position and in correcting slight variations in the corrugations to insure the best results in printing.

Having thus described my invention, what 55 I claim as new, and desire to secure by Letters Patent, is—

1. A font of type consisting of independent bodies each having a character on one end said bodies having substantially the entire 60 surfaces of two opposite sides grooved in parallel transverse lines which extend from edge to edge of the body, and with the corrugations of adjacent bodies adapted to interlock throughout the height of the bodies. 65

2. A font of type consisting of independent bodies each having a character on one end said bodies having opposite sides corrugated continuously from top to bottom in parallel transverse lines extending from edge to edge 70 of the body, and with the corrugations of adjacent bodies adapted to interlock throughout the height of the bodies, each of said bodies having a channel formed in one edge parallel with the character-bearing face and at 75 right angles to the corrugations.

In witness whereof I have hereunto set my hand.

JOHN F. AMES.
